UNITED STATES PATENT OFFICE.

HENRY F. JUERGENS, OF NEW YORK, N. Y.

EAR-PENDANT.

1,106,388.

Specification of Letters Patent. Patented Aug. 11, 1914.

Application filed November 4, 1913. Serial No. 799,069.

To all whom it may concern:

Be it known that I, HENRY F. JUERGENS, a citizen of the United States, and residing at New York, in the county of New York and State of New York, have invented certain new and useful Improvements in Ear-Pendants, of which the following is a specification, such as will enable those skilled in the art to which it appertains to make and use the same.

This invention relates to ear pendants or ornaments, and the object thereof is to provide an improved device of this class which may be securely connected with the lobe of the ear without piercing said ear.

The invention is fully disclosed in the following specification of which the accompanying drawing forms a part, in which the separate parts of my improvement are designated by suitable reference characters in each of the views, and in which:

Figure 1 is a side view of my improved ear pendant and indicating the method of its use;—Fig. 2 a front view of that part of the pendant, which is secured to the ear, detached;—Fig. 3 a section of said part on the line 3—3 of Fig. 1, and;—Fig. 4 a view similar to Fig. 1, but showing a modification.

The invention described and claimed herein consists primarily in that part of the ear pendant which is connected with the ear, and in the practice of my invention, as shown in Figs. 1 to 3 inclusive, I provide an ear attaching part for ear pendants, comprising a loop a which opens upwardly and which is composed of a comparatively rigid front side arm a^2 and a flat thin resilient back side arm a^3 . The front side arm a^2 is curved backwardly, upwardly, outwardly and downwardly to form a hanger a^4 , and the resilient back arm a^3 is curved inwardly, upwardly and outwardly and extends above the front side arm a^2 , and is provided with a backwardly directed extension a^5 .

Normally, when the device is not connected with the ear, as indicated at b , Fig. 1, the back spring arm a^3 is closely adjacent to the back bow a^6 of the front arm a^2 and may bear thereon, but said back arm is very thin and resilient and will operate so as to hold the device on the ear, and the central part of said arm, where it bears on the back of the ear, is widened, as shown at a^7 , and

is also preferably provided with a central longitudinal opening a^8 which facilitates the operation of said arm in holding the device on the ear.

The hanger or depending part a^4 of the front arm a^2 is in the plane of said arm, and also in the plane of the back arm a^3 , and the lower end portion thereof is preferably flattened, as shown at a^9 , and is provided with a transverse perforation or aperture by means of which the pendant proper is suspended therefrom.

In the form of construction shown, the pendant c is composed of a bottom part c^2 and a top part c^3 loosely connected, as shown at c^4 , and the top part c^3 is connected with the hanger a^4 by a link c^5 , but my invention is not limited to the particular form of the pendant, and any suitable device of this class may be employed, my invention consisting, as hereinbefore stated, in the construction of the ear attaching part a .

In Fig. 4 of the accompanying drawing, I have shown a modification in which the forwardly and downwardly curved suspender or hanger a^4 is omitted, the front arm a^2 being terminated at its upper end by an outwardly curved part a^{10} , and in this form of construction, the pendant member is loosely suspended from the bottom part of the front arm a^2 by a link c^5 .

Having fully described my invention what I claim as new and desire to secure by Letters Patent is;—

1. In an ear pendant, an ear attaching member comprising a bottom loop portion which opens upwardly, said loop portion being provided with a front arm which is curved backwardly and then forwardly and provided with a loosely suspended pendant, and with a thin resilient back arm which is curved forwardly and then backwardly and extends above the front arm, and the forward curve of which is opposite the backward curve of said front arm, whereby said arms are adapted to grasp and hold the lobe of the ear.

2. In an ear pendant, an ear attaching member comprising a bottom loop portion which opens upwardly, said loop portion comprising a front arm which is curved backwardly and then forwardly and provided with a depending part having a

loosely suspended pendant, and with a thin resilient back arm which is curved forwardly and then backwardly whereby said arms are adapted to grasp and hold the lobe
5 of the ear.

In testimony that I claim the foregoing as my invention I have signed my name in

presence of the subscribing witnesses this
3rd day of November, 1913.

HENRY F. JUERGENS.
